UNITED STATES PATENT OFFICE.

WALTER S. MENDENHALL, OF CINCINNATI, OHIO, ASSIGNOR TO THE SAMUEL C. TATUM COMPANY, OF CINCINNATI, OHIO, A CORPORATION.

TEMPORARY BINDER.

No. 918,763.

Specification of Letters Patent.

Patented April 20, 1909.

Application filed July 29, 1907. Serial No. 386,110.

To all whom it may concern:

Be it known that I, WALTER S. MENDENHALL, a citizen of the United States, residing at Cincinnati, in the county of Hamilton and 5 State of Ohio, have invented certain new and useful Improvements in Temporary Binders, of which the following is a specification.

My invention relates to a temporary binder of the class employing posts secured 10 to the bottom cover, the upper cover telescoping said posts and being secured thereto at selected places.

The object of the invention is to provide a simple lock for the upper cover.

15 The features of the invention are more fully set forth in the description of the accompanying drawings, forming a part of this specification, in which:—

Figure 1 is a central longitudinal section, 20 partly in elevation, illustrating the locking member in the locked position against the posts. Fig. 2 is a similar view with the post in released position. Fig. 3 is a section on line *x*, *x*, Fig. 2.

25 1 is the bottom cover, having the binding strip 2, and 3 the top cover, having the binding strip 4. 5, 6, represent the posts secured to the strip 2. The strip 4 is provided with orifices through which the posts 5, 6, pass.

30 9, 10, represent lock pieces having guide slots 11 engaging over the pins 12 in the strip 4. The strip 4 is a hollow frame within which the locking pieces slide. The locking pieces are provided with *V*-notches 13,

35 forming an inclined wedge surface 16 adapted to engage the posts 5, 6. The pieces 9, 10, are provided with screw threaded sleeve portions 14 which engage with right

and left screw threads of the rod 15. Thus it will be seen in moving the lock pieces 40 toward their respective posts they will form a wedge between the posts and inside of the casing, making a very rigid friction lock 45 between the parts. This rod has a socket end 16 exposed at one end of the strip 4 and adapted to be turned by a key to operate the lock. It is obvious that when this rod is turned the lock pieces are simultaneously 50 operated to engage and disengage the binding strips, and that a slight turn is sufficient to give a strong wedge-like clamping engagement.

Having described my invention, I claim:—

In a temporary binder, a binding strip 55 provided with posts, a top binding strip formed of an oval shaped tube, provided with orifices through which said posts project, lock pieces between said posts, having their opposite edges bearing against the side wall of the tube, means for limiting the movement of said lock pieces, comprising slots 60 formed in the lock pieces, and pins secured to the tube, passing through said slots, *V*-shaped notches in said lock pieces, providing wedges adapted to be engaged between said posts and side wall of the tube, and a rod having a right and left hand screw thread engaging said lock pieces for simultaneously operating the same, substantially as described.

70 In testimony whereof I have hereunto set my hand.

WALTER S. MENDENHALL.
